UNITED STATES PATENT OFFICE.

ISAAC U. MARLIN, OF SHREVEPORT, LOUISIANA, ASSIGNOR, BY MESNE ASSIGNMENTS,
TO GEORGE T. CUNNINGHAM AND LOUIS T. CUNNINGHAM, BOTH OF SHREVEPORT,
LOUISIANA.

ACETYLENE-GENERATOR.

1,257,088.

Specification of Letters Patent. Patented Feb. 19, 1918.

Application filed May 15, 1914. Serial No. 838,829.

To all whom it may concern:

Be it known that I, ISAAC U. MARLIN, a citizen of the United States, residing at Shreveport, in the parish of Caddo and State of Louisiana, have invented certain new and useful Improvements in Acetylene-Generators, of which the following is a specification.

An object of my invention is to provide 10 an acetylene gas generating apparatus, so constructed that a pressure-actuated device arranged in the generating chamber acts through variation in the gas pressure to control the carbid feed and thus cut off or 15 open the carbid supply as the case may be, the least variation of pressure acting to close or open the supply as the variation may be above or below the pressure desired and at which the apparatus is adjusted to 20 work.

A further object is to provide a pressure regulator which may be set to operate at a high pressure or at a low pressure and at the varying pressures between as the occasion 25 may require and which is active under all conditions to perform a successful operation.

Yet another object is to so construct the parts that the generator is portable and the 30 apparatus may be moved from place to place without danger of the accidental supply of carbid to the water, and without danger of the water finding its way into the carbid receptacle. It is also an object to arrange 35 the parts in a manner that in the filling of the water tank all possibility of the water rising above a predetermined level and thus flooding the carbid receptacle is precluded.

With other objects in view, which will be referred to, my invention consists in the 40 peculiar combination and novel arrangement of parts, such as will be hereinafter more fully described in connection with the 45 accompanying drawing and more particularly pointed out in the appended claim.

In the drawing:—

Figure 1 is a view in side elevation of the 50 generator tank with parts broken away more clearly to illustrate the structure.

Fig. 2 is a vertical sectional view through the disclosure in Fig. 1.

Fig. 3 is an enlarged detail sectional view through the pressure regulator.

Fig. 4 is an enlarged fragmentary sectional view of the carbid hopper valve seat. 55

The generator tank 1 has a carbid hopper 2 mounted in the upper end thereof and it is the intention that the generator tank be filled with water to the level indicated at 3 60 and that carbid be dropped from the hopper into the water where gas is formed and rises to the gas storage chamber 5 which is provided in the upper part of the generator tank above the water level. 65

The carbid hopper 2 is made tapered toward its lower end and at its extreme lowest point has an outlet opening 6. A flange 7 is placed around the upper end of the tank 1 and the upper edge of this tank 70 and the upper edge of the carbid hopper 2 are rolled over to be received in a recess formed on the upper face of the flange ring 7, a generator head 8 being secured upon this flange ring 7 by bolts or in any other 75 suitable manner, and provided with a carbid supply-opening 9 which is closed by a screw plug 10.

A carbid valve 11 is carried by a bell-crank lever 12 mounted adjacent the carbid opening 6 and may be swung to a position to close against the valve seat 13 provided around the opening 6 and which latter has a knife edge to be received against the valve 11 to form a tight joint. A pressure 80 actuated device is provided to control the opening and closing movements of the valve 11 and this pressure regulator comprises a diaphragm chamber 14 which is connected to have communication with the gas storage-chamber 5 a diaphragm 15 is mounted in the diaphragm chamber and a stem 16 is connected with the free end of the bell-crank lever 12 and is secured to this diaphragm 15 so that as the diaphragm is actuated the valve will be opened or closed. 85

A coil spring 17 is received around the stem 16 behind the diaphragm 15 and an adjusting screw 18 is provided to adjust the tension which this spring exerts against the 90 diaphragm. This stem 16 extends through the adjusting screw 18 which is made hollow and at its outer end is screw threaded, the nut 19 being received thereon to be screwed up tight against this adjusting screw 18 to 100 hold the valve 11 closed against operation.

A filling tube 20 is connected with the generator tank preferably in the body por-

tion, an overflow tube 21 is connected preferably adjacent the filler tube 20 and at a height that the water will be always maintained at the level indicated by the dotted line at 3; and these tubes are provided with valves 22 and 23, a common operating lever 24 being provided to open the valves simultaneously when it is desired to fill the generator tank and thus preventing an 10 over-supply of water to the tank.

The bottom of the tank is preferably made dished and a sludge paddle 25 is mounted to be rotated adjacent the bottom, a crank 26 being provided to extend through 15 the side of the tank to be at a position to be operable from the exterior thereof. A sludge discharge-pipe 27 is connected with the bottom of the tank 1 and this pipe is controlled by a valve 28.

20 A water seal tank 29 is connected with the side of the generator tank 1 to be filled with water approximately to the point indicated by the dotted line a gas outlet tube 30 is connected with the chamber 5 of the 25 generator tank and is extended down to open beneath the water level in this flashback tank. It is the intention that this tube 30 shall be open at all times and shall permit the flow of gas from the chamber 5 30 down through the liquid in the tank 29 and thence out through the gas supply-pipe 31 to the point of consumption, and the pressure gage 32 and safety valve 33 are connected with this tube 30 thus placing these 35 parts at a point to be operated by the gas at a representative pressure.

From the foregoing it will be seen that I have devised an acetylene gas generator mechanism which can be used to accomplish the object as herein set forth and one which is automatic in its operation to supply a constant flow of gas at the desired pressure, further, one in which the possibility of accidents is precluded as the water 40 seal prevents any back fire into the generating chamber and the connection of the 45

generator tank head with the tank is so formed that if for any reason the escape safety valve should cease to operate this head would be forced from the tank before 50 the pressure becomes sufficiently excessive to burst the generator tank.

While I have herein shown and described one specific form of my invention, it will be understood that slight changes might 55 be made in the form and arrangement of the several parts without departing from the spirit and scope of my invention, and hence I do not wish to be limited thereto except for such limitations as the claim may 60 import.

I claim:—

The combination with a receptacle of a hopper mounted therein and provided with an outlet opening adapted to communicate 65 the interior of said hopper with the interior of said receptacle; a bracket secured to the hopper; a bell crank lever pivotedly connected to the bracket; a valve secured to one end of the bell crank lever and adapted 70 to seat upon said opening exteriorly to said hopper; a diaphragm chamber secured to and communicating with the interior of the receptacle; a spring pressed diaphragm carried within said chamber; an elongated 75 screw-thread portion mounted in the end of the diaphragm chamber, said threaded portion being adapted to regulate the spring tension of said diaphragm; a stem directly connecting the diaphragm and said bell 80 crank lever and extending through the diaphragm and the hollow screw-threaded portion; and a nut carried by the outer end of said stem, said nut being adapted to limit the diaphragm in its movement effectuating 85 the opening of said valves.

In testimony whereof I affix my signature in presence of two witnesses.

ISAAC U. MARLIN.
